UNITED STATES PATENT OFFICE.

JAMES H. BURROW AND GEORGE A. BURROW, OF SPOKANE, WASHINGTON, ASSIGNORS
TO BURROW MANUFACTURING COMPANY, OF SPOKANE, WASHINGTON, A COR-
PORATION OF WASHINGTON.

REPAIR SHIELD.

Application filed January 12, 1924. Serial No. 685,795.

To all whom it may concern:

Be it known that we, JAMES H. BURROW and GEORGE A. BURROW, citizens of the United States, residing at Spokane, in 5 Spokane County and State of Washington, have invented certain new and useful Improvements in Repair Shields, of which the following is a specification.

The present invention relates to improvements in repair shields or boots for use between the outer casing and inner tubes of 10 tires to close a puncture or reinforce a damaged casing. The primary object of the invention is the provision of a device of this 15 character which is comparatively inexpensive in cost of production and which is so fashioned and constructed that it may with facility be applied for use without the necessity for expert knowledge on the part of 20 the user. When in position for use on the inner tube, the shield by its formation and construction readily adjusts itself when the tire is inflated and fits neatly into place to present a smooth structure between the casing 25 and inner tube. Due to the wrapping of the shield about the tube and the formation of the shield when in place, the danger of pinching the inner tube is eliminated, and means are provided whereby the shield 30 is properly positioned and is anchored in this position against displacement within the damaged casing of the tire.

The invention consists in certain novel 35 features of construction and combinations and arrangements of parts for accomplishing the above ends, as will hereinafter be more fully pointed out and claimed.

In the accompanying drawings we have 40 illustrated one complete example of the physical embodiment of our invention wherein the parts are combined and arranged in accordance with the best mode we have so far devised for the practical application of the principles of our invention.

45 Figure 1 is a perspective view of a shield according to our invention shown in rolled position, ready to be unrolled and wrapped about an inner tube.

Figure 2 is a view of the shield unrolled 50 and showing the inner face thereof.

Figure 3 is a detail sectional view, enlarged showing an edge of the shield.

Figure 4 is a detail sectional view en-

larged showing an edge of the intermediate anchoring portion of the shield. 55

As now in actual use the shields are fashioned in various sizes and are manufactured on suitable mandrels adapted for the purpose in order that they will conform to the curvature of the tire. The shields are prepared or manufactured for shipment and sale in the form shown in Figure 1 of the drawings and they may readily be unrolled from this form for facile application to the tire. 65

The shield as shown is preferably of fabric either in a single thickness or of cemented layers, and is formed in three portions as the inner narrow portion 1 which is wrapped directly on the tube; the outer 70 wrapper portion 2 which is narrower than the inner portion; and an intermediate anchoring portion 3. The portion 1 is designed to be wrapped on the tube with the intermediate portion 3 at the inner side of 75 the tube, and the wrapper portion 2 is designed to be wrapped around the inner portion as indicated in Figure 1.

At its ends the intermediate portion is provided with extensions 4 and 5 projecting 80 beyond the greatest width of the shield, and as seen in Figure 4 these lips or extensions are comparatively thinner than the body of the shield or the anchoring portion 3 in order that they may lie snugly between the 85 tube and the casing of the tire and prevent the former being pinched between the casing and the shield.

The outer edges of the shield are also 90 much thinner and more flexible than the body of the shield as indicated in Figure 3 where a rubber strip 6 is cemented to the outer face of the shield. As shown this strip may be cemented to a layer of the fabric of which the shield is composed. 95 The presence of these comparatively thin and more flexible edges for the shield not only prevents pinching of the tube, but they also insure a smooth joint for the encased shield. The edge strip as indicated in Figure 1 passes around the edge of the shield on its outer face, while the inner face of the shield, as indicated in Figure 2 is a smooth plane face for contact with the inner tube and with the inner wrapped part of 100 105 the shield.

The shields are of the proper length to be wrapped or passed twice around the tube leaving the ends of the shield free for movement when the tube is inflated in order that the tube may adjust itself to the inflated tire. The intermediate portion 3 however remains stationary at the inner side of the tube and within the casing, and because of its increased thickness and curvature it is less flexible than the wrapper portion of the shield. Thus the intermediate portion becomes anchored at the inner side of the tire tube and remains stationary when the tube is inflated, but permits the two wrapped portions of the shield to adjust themselves as the cross-area of the tube is increased. After the tube has been inflated the shield is held in stationary position and is prevented from creeping around the tire because of the thin flexible edges of the shield which permit a close frictional contact between it and the tube and its casing.

Because of the construction of the shield with its intermediate semi-rigid anchoring portion, which conforms in curvature to the inner portion of the tire tube, expert knowledge in applying the shield is not required, as the utility and applicability of this anchoring portion to the inner portion of the tube will readily be apparent and the anchoring portion could not within reason be placed in the incorrect position with relation to the tube. With the intermediate portion anchored in stationary position it will be apparent that the two ends of the shield are held in close frictional contact and a double hold is secured not only on the shield itself but between the shield and tube

and between the shield and casing, to prevent loosening of the shield after the tire has been inflated.

From the above description taken in connection with the drawings it will be evident that we have provided a device of this character which fulfills the condition set forth as the object of our invention, and as is evidenced by the extensive use to which the device has been applied in the market.

Having thus fully described our invention what we claim as new and desire to secure by Letters Patent is—

1. A repair shield having an intermediate anchoring portion adapted to engage the inner side of a tire tube and inner and outer portions one of which is adapted to wrap around the tube and the other to encircle the wrapped portion.

2. A repair shield having an intermediate anchoring portion adapted to engage the inner side of a tire tube, thin, flexible extensions at the ends of said anchoring portion, and said shield having a thin flexible edge strip.

3. A repair shield having a stiff, intermediate anchoring portion and thin flexible extensions on said anchoring portion, an inner integral portion adapted to wrap about a tire tube, an outer integral portion adapted to encircle the inner wrapped portion, and a thin flexible edge strip on said portions.

In testimony whereof we affix our signatures.

JAMES H. BURROW.
GEORGE A. BURROW.
